Attorneys.

UNITED STATES PATENT OFFICE.

THOMAS D. RYAN, OF BUFFALO, NEW YORK, ASSIGNOR OF ONE-HALF TO JOHANN H. W. KUHLMANN, OF BLUE LAKE, CALIFORNIA.

ANTISLIPPING ATTACHMENT.

Application filed May 5, 1927. Serial No. 189,075.

This invention relates to an anti-slipping attachment for canes, crutches and the like, one of the objects being to provide a simple and efficient device of this character which can be applied readily to an article such as stated and which can be quickly adjusted to either active or inactive position, means being employed for holding it firmly in either of the two positions mentioned.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown. In said drawings,

Figure 1 is a view partly in elevation and partly in section showing the device as in use to prevent slipping.

Figure 2 is an elevation showing the parts assembled as in Figure 1 but viewed at right angles to said figure.

Figure 3 is a section on line 3—3, Figure 2.

Figure 4 is a side elevation showing the device moved to an intermediate position.

Figure 5 shows the attachment held out of active position.

Referring to the figures by characters of reference 1 designates the shank portion of a cane or crutch provided, at its lower end, with the usual rubber ferrule or tip 2.

The attachment constituting the present invention includes a yoke 3 having opposed arms 4 which are extended to diametrically opposite points on the shank 1 and attached to the shank by means of pivot pins 5 extending into the shank. The yoke 3 straddles the shank and is provided at one end with a laterally extended ear 6 to which is pivotally connected a retaining latch 7. Another ear 8 is extended laterally from the other end of the yoke and has a keeper 9 thereon. When the yoke is in engagement with the shank 1 the latch 7 can swing into engagement with the keeper 9, thereby to hold the yoke and the arm 4 against movement relative to the shank and retaining the arm substantially parallel with the longitudinal axis of the shank 1.

A cup-like foot 10 is provided for receiving the lower end of the tip 2, this foot being formed with a spur 11 extending therefrom. Diametrically opposed arms 12 extend from the cup and are pivotally connected to the arms 4 at points between the yoke 3 and the pivot 5, as shown at 13.

When the attachment is not in use the foot 10 is in engagement with a spring finger 14 extending from the shank 1, the foot being swung onto this finger by pressing it thereagainst.

At this time the yoke 3 is astride the shank 1 and held thereto by means of the latch 7. When it is desired to use the attachment to prevent slipping the latch 7 is moved to release the yoke 3 and said yoke is swung downwardly after the foot 10 has been disengaged from the finger 14. This downward movement will be sufficient to bring the foot 10 beneath the end of the tip 2 whereupon this foot can be swung to position under the tip. By then swinging the yoke 3 upwardly the arm 4 will pull on the arm 12 with the result that the cup-like foot 10 will move onto the lower end of the tip 2 as shown in Figures 1 and 2 and the yoke 3 will again be brought astride shank 1 where it can be held by means of the latch 7.

With the parts thus located they cannot become accidentally displaced relative to each other and the spur 10 will act to prevent slipping, as will be obvious.

The attachment herein described is especially useful on wet or frozen surfaces.

What is claimed is:

1. The combination with a shank, and a tip upon the end of the shank, of a yoke, lever arms extending therefrom pivotally connected to the shank, said yoke being movable into and out of position astride the shank, means for fastening the yoke in position when astride the shank, a cup-like foot, means thereon for engaging a surface to prevent slipping, arms connecting the foot to the arms of the yoke, said yoke and arms being movable relative to the shank to shift the foot into and out of position about the end of the tip, and means on the shank for extending into the foot to hold said foot in inactive position above the tip.

2. The combination with a shank, and a tip upon the end of the shank, of a yoke, lever arms extending therefrom, means extending

through the arms and into the shank for pivotally connecting the arms to the shank, said yoke being movable into and out of position astride the shank, a retaining latch connected 5 to the yoke for bridging the same to hold the yoke against pivotal movement relative to the shank while astride the shank, a cup-like foot,

means thereon for engaging a surface to prevent slipping, and spaced arms integral with the foot and pivotally connected to the respective arms of the yoke. 10

In testimony that I claim the foregoing as my own, I have hereto affixed my signature.

THOMAS D. RYAN.
